UNITED STATES PATENT OFFICE.

DANIEL L. HOLDEN, OF PHILADELPHIA, PENNSYLVANIA.

FREEZING-CYLINDER FOR ICE-MACHINES.

SPECIFICATION forming part of Letters Patent No. 730,018, dated June 2, 1908.

Application filed July 30, 1901. Serial No. 70,225. (No model.)

To all whom it may concern:

Be it known that I, DANIEL L. HOLDEN, a citizen of the United States, residing at Philadelphia, in the county of Philadelphia and State of Pennsylvania, have invented certain new and useful Improvements in Freezing-Cylinders for Ice-Machines, of which the following is a specification.

My invention relates to improvements in freezing-cylinders for regealed ice-machines, and has for its object the more perfect and continuous distribution of the anhydrous ammonia to the entire inner circular surface of the freezing-cylinder. When the ammonia is introduced to the cylinder, unless some means is adopted to distribute it to the cylinder's whole surface before evaporation takes place its full effect is lost, and hence imperfect results and the necessity of more frequent reliquefaction, pumpage, &c. Therefore to overcome this loss and an only partial effect I have devised means for the liquid's longer and greater contact with the cylinder-surface until it shall be fully covered and have thus greatly increased the effect produced over the methods heretofore adopted where only a small portion of the surface was covered by the liquid.

My invention is illustrated in the accompanying drawings, in which—

Figure 1 is a central vertical section of the freezing-cylinder. Fig. 2 is a transverse section on line X X, Fig. 1, looking to the right with the retaining-plates as when formed in single circumferential sections. Fig. 3 is a transverse section, also on line X X, Fig. 1, looking to the left, showing the retaining-plates as formed in multiple circumferential sections.

Similar numerals of reference indicate similar parts throughout the views.

The freezing-cylinder has a circumferential shell 1, secured to heads 2 3, from which are trunnions 4 5, by which the cylinder is supported for rotation, the trunnions being journaled in bearings 6 7, secured on ends 8 9 of the inclosing tank. At one end of the cylinder through its trunnion 4 is a liquid-ammonia inlet-pipe 10, extending within the cylinder and having a down-tending quarter-turn 11. At the opposite end through trun-

nion 5 is an open discharge-pipe 12, through which the ammonia-gas passes away.

Within the cylindrical shell 1 and closely lying thereto is a lining 14, which may be of any material having suitable interstices in its structure wherein the liquid ammonia will be deposited and retained as the shell rotates while it flows in through pipe 10, or the lining may be of an absorbent material, spongy in its nature and adapted to be saturated, and thereby retain the liquid. Interior to lining 14 are retaining-plates 15, which may be made, as seen in Fig. 2, in one circumferential piece, having lugs 16 secured at their adjacent edges tapped with right and left hand screw-threads and having a right-and-left screw 17, whereby the plates 15 may be contracted for insertion and thereafter expanded to the lining 14. In Fig. 3 the retaining-plates 18 are inserted in multiple parts circumferentially, with a lug-bolt 19 secured to one edge of each plate, a bracket 20 being secured to the edge of the adjacent plate, a hole therein through which bolt 19 is passed, and nuts 21 screwed on the bolt at either side of bracket 20 and by which plates 18 are drawn together or forced apart for the purpose as heretofore explained. Other means might be employed to adjust the plates and still be within the scope of my invention. The retaining-plates have perforations 20^x therethrough by which the liquid ammonia percolates to the lining 14. The cylinder is rotated by means of the sprocket-wheel 22, secured to trunnion 5. Tap-bolts 23, passing through the retaining-plates and into the cylinder-shell, secure the plates to the cylinder for rotation therewith or from shifting. Annular rings 24 25 are secured within heads 23 to prevent the contact of ammonia with the heads, so that refrigeration may take place only upon the circumferential surface of the cylinder.

I claim—

1. In a machine of the character described, a rotatable cylinder, an absorbent lining therein, perforated retaining-plates within the lining and means to increase or to decrease the diameter of the lining-plates.

2. In a machine of the character described, a rotatable cylinder, an absorbent lining there-

in, retaining means for the lining composed of circumferential plates, which, at their longitudinal edges are spaced apart and means to decrease or increase the space and thereby decrease or increase their diameter.

3. In a machine of the character described, a rotatable cylinder, a liquid-retaining lining therein, retaining means for the lining composed of rings of multiple circumferential plates, a longitudinal space between the edges

of adjacent plates, and means to increase or decrease the space and thereby the diameter of the retaining-ring.

In testimony whereof I affix my signature in presence of two witnesses.

DANIEL L. HOLDEN.
